UNITED STATES PATENT OFFICE

MORRIS P. KIRK, OF LOS ANGELES, CALIFORNIA

ILLUMINATED SIGN

Application filed May 25, 1927. Serial No. 193,981.

This invention relates to illuminated signs. A common form of two-color sign has a plate-glass upon which letters, numerals, or other configurations of a certain color are placed. These configurations are usually white and the area surrounding the configurations is of a different color. Placed in back of the plate-glass is a housing in which a lamp is situated. Light-rays from the lamp are passed through the plate-glass and the sign is thus illuminated. The configurations appear in one color and the surrounding area appears in another color. This type of sign is not entirely satisfactory in view of the fact that the configurations are not distinct at any distance.

It is an object of this invention to provide a sign in which the configurations are very distinct even at great distances.

Other objects and advantages of the invention will appear in the following description.

My invention may be best understood by referring to the accompanying drawing for a detailed description.

In the drawing:

Fig. 1 is a face view of a sign having the features of this invention incorporated therein.

Fig. 2 is a cross section taken on the line 30 2—2 of Fig. 1.

Fig. 3 is a fragmentary section of a light-pervious member.

In the drawing the numeral 11 designates the housing of the invention. Mounted in the housing is a socket 12 which supports the light source of the invention, which light source is provided in the form of a filament-lamp 13. The housing 11 has a somewhat segment-shaped chamber 14 having a reflecting face 15 which is adapted to reflect incident light-rays 16 forward from the front of the housing 11 as indicated at 18. The front of the housing 11 is provided with a cover-piece 19 having an opening 20 directly in front of the lamp 13, which opening 20 is

provided with a colored glass 21 which transmits light of a certain color. The portion of the cover-piece 19 which is in front of the chamber 14 has an opening 22 which is closed by a light-pervious member 25.

Referring to the details of the construction of the housing 11, it will be noted that it consists of three parts in addition to the glass or lens 21 and the glass sign plate 25. The rear housing member 11^a is of cup shape and has a peripheral flange 11^b normal to its base wall 11^c. In installing the sign in its place of use, the base wall 11^c of the housing is engaged and clamped to the member or structure supporting the sign by the lamp socket 12. The main housing member 11^d has a depending portion 11^e forming the segment-shaped chamber 14 and a rearwardly extending tubular flange 11^f contoured to have a telescoping engagement with the flange 11^b of the supporting member 11^a. The cover-piece 19 has a forward tubular portion 19^a which contains the glass or lens 21 and a depending frame portion 19^b which supports the sign member 25 and the cover-piece 19^c also has a peripheral flange 19^c which telescopes over the front edge of the main housing member 11^d, whereby the sign member 25 is supported and held in contact with the front edge of the housing member 11^d. This construction provides a housing, in which the socket and lamp are positioned to coincide with the tubular portion thereof, and having a depending segmental portion with the glass 21 constituting the front wall of the so tubular portion and the glass sign 25 constituting the front wall of the depending segmental portion.

In use, the cup-shaped housing member 11^a and the socket 12 may be permanently installed in place and the main housing member 11^d, carrying the cover-piece 19, the glass 21, and the sign 25, then applied with its tubular portion 11^f slidably telescoped upon the member 11^a. By this arrangement the

entire device is supported by its cup-shaped housing member 11^a and may easily be removed therefrom for purposes of inspection, repair, or replacement. It should be evident 5 that the tubular portion of the housing, together with the glass or lens 21 and the lamp, constitutes an indicator or pilot light to direct attention to the depending sign which conveys the detailed information to the mind 10 of the observer.

The light-pervious member 25 may be made of any suitable translucent or pellucid material such as glass. The light-pervious plate 25 is so placed below the filament 26 15 of the lamp 13 that light-rays 27 pass through the light-pervious plate from the upper edge 28 thereof.

The light-pervious plate is provided with configurations 29 which in the drawing are 20 in the form of letters which spell the word "exit". These configurations 29 are preferably intaglio. The configurations may be formed by etching or by sand-blasting. Sand-blasting is the preferable way, since it 25 provides a very rough surface which is very satisfactory for reflecting light-rays. As shown in Fig. 2 the light-rays 27 passing downward through the light-pervious-plate 25 strike the roughened surfaces of the configurations 29 and are projected forward as 30 shown at 31. The configurations 29 show up very bright and are distinct even at a comparatively long distance.

It is desirable to have the area surrounding 35 the configurations 29 of a different color so as to enhance the distinctness of the configurations 29. This I accomplish by placing a colored light-transmitting member 33 in contact with the back surface of the light-pervious plate 25. The configurations 29 are the only parts of the light-pervious plate which are not covered by the colored light-transmitting member 33. This light-transmitting member may be of any suitable color, 40 red, for example. The reflected light rays 18 which are reflected by the reflector 15 are red when they pass through the light-pervious plate 25, thus surrounding the white configurations 29 with a background. The means for 45 transmitting only red light-rays may be of various forms; for example, it would be possible, in place of having a separate colored light-transmitting member in the position shown, to color the light-pervious plate 25 50 or to place a colored light-transmitting member above the chamber 14 so that only red light-rays would be transmitted to the reflector 15.

From the foregoing description it will be 60 seen that the important part of the invention is to provide a luminous sign which is distinct at a distance. This feature of the invention is accomplished by utilizing light-rays which pass directly through the edge of 65 the light-pervious plate 25 and are deflected

forward by intaglio configurations, and by utilizing reflected light-rays which pass through the light-pervious plate from the back thereof.

I claim as my invention:

1. A sign comprising: a rear housing member having a base wall and a flange normal to said wall; a main housing having a flange telescopically engaging the flange of said rear housing member; a lamp socket in said rear housing member; a light bulb in said socket and extending into said main housing, said main housing having a depending portion; and a light-pervious sign plate positioned in the front wall of said depending portion and having sign configurations thereon adapted to become luminous when rays from said source enter an edge of said sign plate, said depending portion receiving light rays from said light bulb and having a reflecting surface for projecting said light rays through said sign plate. 70 75 80 85

2. A sign comprising: a cup-shaped rear housing member having a flange; a main housing member having an upper portion and a depending lower portion with its upper portion provided with a rearwardly projecting flange telescopically engaging the flange of said cup-shaped member; a light-pervious plate in the front wall of said upper portion of the main casing member; a light source in the upper portion of said main housing member, said flanges, said light source, and said plate being axially aligned; and a light-pervious sign plate positioned in the front wall of the depending portion of the housing and having sign configurations thereon adapted to become luminous when rays from said source enter an edge of said sign plate, said depending portion receiving light rays from said light source and having a reflecting surface for projecting said light rays through said sign plate. 90 95 100 105

3. A sign comprising: a cup-shaped rear housing member having a flange; an open-front main housing member having an upper portion and a depending segment-shaped lower portion and provided with a flange projecting rearwardly from said upper tubular portion and telescopically engaging the flange of said cup-shaped member; a front cover-piece having an upper tubular portion and a lower segment-shaped portion and provided with a rearwardly extended peripheral flange telescopically engaging the peripheral wall of said main housing member; a light-pervious lens disposed in the front wall of the tubular portion of said cover-piece; a light-pervious sign plate disposed in the front wall of the lower segment-shaped portion of said cover-piece and having sign configurations thereon adapted to become luminous when contacted by rays of light entering said sign plate through an edge thereof; and a light 110 115 120 125 130

source positioned in said cup-shaped member directly above said edge and axially aligned with said lens to provide a pilot light, said depending portion of the housing receiving light rays from said light source and having a reflecting surface for projecting said light rays through said sign plate.

5 In testimony whereof, I have hereunto set my hand at Los Angeles, California, this
10 20th day of May, 1927.

MORRIS P. KIRK.
